THE NORRIS PETERS CO., PHOTO-LITHO., WASHINGTON, D. C.

UNITED STATES PATENT OFFICE.

GEORGE HOWLETT DAVIS, OF BROOKLYN, NEW YORK.

MACHINE FOR FORMING STENCILS FROM WHICH MUSIC-SHEETS ARE PRINTED.

SPECIFICATION forming part of Letters Patent No. 703,389, dated July 1, 1902.

Application filed April 17, 1901. Serial No. 56,269. (No model.)

To all whom it may concern:

Be it known that I, GEORGE HOWLETT DAVIS, a citizen of the United States, and a resident of Brooklyn, in the county of Kings 5 and State of New York, have invented a certain new and useful Machine for Forming Stencils from which Music-Sheets are Printed, of which the following is a specification.

My present invention relates to an improved 10 machine for forming stencils from which music-sheets are printed, and has for its object to provide a very simple device of this character which will be very easy to operate and one wherein the stencil being operated upon 15 may be readily manipulated.

In self-playing musical instruments operated either pneumatically or electrically through the medium of a perforated note-sheet it has become customary to provide 20 such note-sheets with suitable characters or marks to designate the various expressions in tone and speed to be given the composition during its performance; and it is the purpose of the present invention to provide 25 a machine for forming the sheet-stencils from which to print or mark the said expression characters upon the finished sheet.

The invention comprises the novel features of construction and combination and 30 arrangement of parts hereinafter described in detail and then more definitely pointed out in the claims which conclude this specification.

In order to enable others skilled in the art 35 to which my invention belongs to make, use, and operate the same, I will proceed to describe the machine in detail, reference being had for this purpose to the accompanying drawings, in which—

40 Figure 1 is a perspective view of a complete machine constructed in accordance with my invention. Fig. 2 is a detail side view, partly in section, of a portion of the machine.

Referring to the drawings, the reference 45 numeral 1 designates the base of the machine, which may be made in any desired form and which is provided upon each side with two bearings 2 and 3, one pair of which is in rear of the other. Within the two front 50 bearings 2 is journaled a receiving-roller 4, having fixed to one end thereof a large milled head 5, for a purpose presently to appear.

Within the two rear bearings 3 is journaled a delivery-roller 6, the shaft 7 of which is provided upon one end with a pinion 8, 55 which meshes with a gear-wheel, said gear-wheel being mounted upon a short shaft 10, journaled in close proximity to the shaft 7 of the delivery-roll, as will be seen. The gear-wheel 9 is provided with a crank-handle 60 12 or some other means whereby the same may be readily operated to communicate motion to the delivery-roll 6.

Secured to opposite sides of the frame 13 intermediate the receiving and delivery-rolls 65 and somewhat above them is a metal bar 14, to which is attached a metal plate 15, having side pieces 16, and upon this plate between the side pieces is supported a wooden cutting block or platen 17, preferably arranged 70 on an incline, over which the stencil to be cut passes in its movement to and from the delivery and receiving rolls.

To the under side of the metal plate 15 are attached the inwardly-bent ends of a yoke-bar 18, which latter is located above the wooden cutting block or platen 17 and lies parallel therewith, as shown. Tapped through this yoke-bar 18 is a series of clamping-screws 19, which are arranged to firmly hold the 80 metal pattern stencil-plate 20 upon the stencil-sheet 21 and upon the wooden cutting block or platen 17.

In order that the operator may have his tools in close reach, I have provided a tool 85 support or holder, which consists of a bar 22, located slightly above and in rear of the yoke-bar and which has its ends 23 bent downward and secured to opposite sides of the metal base-frame. This bar 22 is provided with a series of notches or recesses 90 23 to receive and retain the tools used by the workman.

It is desirable that the stencil-strip 21 be held taut during operation, and for this purpose I have provided a friction piece or spring 24, which is attached at one end to the shaft of the roller 4 or in any other suitable manner and has its opposite end free and acting by friction or pressure upon the end of the receiving-roller 4. The degree of pressure given this friction-spring is regulated by a thumb-screw 25, tapped through the frame of the machine, as shown in Fig. 1.

The operation of the machine may be briefly stated, as follows: The stencil-sheet to be marked or cut is first rolled upon the delivery-roll 6, which roll is preferably removably mounted, and its end is then passed upward over the cutting block or platen 17 and from thence passed downward and secured to the receiving-roll 4, which latter is provided with any suitable means by which the said end of the stencil-sheet may be secured thereto. This stencil-sheet has marked thereon in any suitable manner and at the proper points the particular expression-marks to be cut therein, and as these marks appear over the cutting block or platen during the movement of the sheet, which is accomplished by turning the milled wheel 5, the operator places his metal pattern-plate 20, bearing the appropriate mark, upon said sheet, as shown, and then 15 clamps the same firmly in position by means of the clamping-screws 19. The operator now takes his tools, which consist of sharp cutting instruments, and removes or cuts the material from the sheet, so as to leave openings therein to represent the particular expression-mark, such as "retard," "tempo," and the like, as illustrated in the drawings. The stencil-sheet is also cut with a deviating or zigzag line of perforations, (represented by 20 the numerals 26.) When the sheet or stencil has been cut at all the points indicated, it is rewound upon the delivery-roll by simply rotating the gear-wheel 9 by means of the handle 12. The stencil is now complete and 25 may be removed and passed through a printing-press in contact with the inking-roller, the ink passing through the apertures in the sheet and upon a music-sheet to be marked.

What I claim is—

- 40 1. In a machine for forming sheet-stencils, the combination with a suitable base-frame, of a delivery-roll and a receiving-roll journaled in said frame, a cutting block or platen arranged above the said rolls and over which the sheet-stencil is moved during its passage from one roll to the other and means for clamping a stencil-plate upon said block or platen.
- 45 2. In a machine for forming sheet-stencils, the combination with a suitable base-frame, of a delivery-roll and a receiving-roll journaled in the said frame, a cutting block or platen arranged above the plane of said rolls and over which the stencil-sheet is moved during its passage from one roll to the other, clamping devices for holding a stencil-plate to the face of the platen and means for operating said rolls.
- 50 3. In a machine for forming sheet-stencils, the combination with a suitable base-frame, of a delivery and a receiving roll journaled in said frame, a cutting block or platen arranged above the plane of said rolls and over which the stencil-sheet is passed during its movement to and from the rolls, and suitable clamping means adapted to bind the stencil-sheet to the face of the cutting-block, for the purpose specified.

4. In a machine for forming sheet-stencils, the combination with a suitable base-frame, of a delivery and a receiving roll journaled in 70 said frame, a cutting block or platen arranged intermediate and above the plane of said rolls and over which the stencil-sheet passes, means for clamping a stencil-plate to the face of the platen and a friction device acting upon the 75 said receiving-roll, substantially as described.

5. In a machine for forming sheet-stencils, the combination with a suitable base-frame, of a delivery and a receiving roll journaled in 80 said frame, a cutting block or platen arranged intermediate and above the plane of said rolls, and a tool-holder mounted upon the frame adjacent to the said cutting-block.

6. In a machine for forming sheet-stencils, the combination with a suitable base-frame, 85 of a delivery and a receiving roll journaled in said frame, a milled head secured to one end of said receiving-roll, and a cutting block or platen mounted upon the frame and arranged intermediate the two rolls for the purpose 90 specified.

7. In a machine for forming sheet-stencils, the combination with a suitable base-frame, of a delivery and a receiving roll journaled in 95 said frame, a cutting block or platen arranged intermediate said rolls, a friction-plate having one end free to act upon one end of the receiving-roll, a thumb-screw for regulating the pressure of said friction-plate, and means for operating the said rolls.

8. In a machine for forming sheet-stencils, the combination with a suitable base-frame, of a delivery and a receiving roll journaled in said frame, a cutting block or platen mounted upon the frame intermediate the said rolls, a 105 pinion upon one end of the delivery-roll, a gear-wheel meshing with said pinion, means for operating the gear-wheel, a milled head upon one end of the receiving-roll, and a clamping device arranged above the cutting-block, for the purpose specified.

9. In a machine of the class described, the combination with a suitable frame, of a delivery-roll and a receiving-roll journaled in 115 said frame, an inclined cutting block or platen fixed to the frame and over which the sheet-stencil is caused to move during its passage from one roll to the other and means for clamping a stencil-plate to the face of said block or platen.

10. In a machine of the class described, the combination with a suitable base-frame, of a sheet delivery roll and a receiving roll journaled in said frame, an inclined cutting block or platen arranged above the plane of said 125 rolls and over which the sheet-stencil is caused to move during its passage from one roll to the other and means for clamping the stencil-sheet to said block or platen.

11. In a machine of the class described, the combination with a suitable base-frame, of a sheet delivery roll and a receiving roll journaled in said frame, an inclined cutting block or platen arranged intermediate and above

the plane of said rolls, clamping devices arranged above the cutting-block and means for imparting a rotary movement to said rolls.

12. In a machine of the class described, the combination with a suitable base-frame, of a delivery-roll and a receiving-roll journaled in said frame, a cutting block or platen arranged intermediate said rolls and over which the sheet-stencil to be cut is caused to move during its passage from one roll to the other, and independent means for rotating said rolls.

13. In a machine of the class described, the combination with a suitable base-frame, of a delivery-roll and a take-up roll journaled in said frame, a block-support secured to the frame intermediate the rolls, a cutting block or platen removably attached to said support, and means for rotating the rolls to cause a sheet-stencil to move from one roll over the cutting block or platen and to be wound upon the other roll.

14. In a machine of the class described, the combination with a suitable frame, of a delivery-roll and a take-up roll journaled in said frame, an inclined block-support carried by the frame and extending above the plane of the rolls, a cutting block or platen carried by

said support, means for clamping a stencil-sheet to the face of the cutting-block and means for rotating said rolls.

15. In a machine of the class described, the combination with a suitable frame, of a delivery-roll and a take-up roll journaled in said frame, a block-support fixed to the frame intermediate the rolls, a cutting block or platen carried by said support, a bar disposed above the cutting block or platen, and clamping-screws tapped through said bar and adapted to clamp a stencil-plate to the face of the cutting block or platen.

16. In a machine of the class described, the combination with a sheet delivery roll and a take-up roll, of a cutting block or platen arranged above and overhanging one of said rolls, and means for clamping a stencil-plate to the face of the cutting block or platen.

Signed at Brooklyn, in the county of Kings and State of New York, this 8th day of April, A. D. 1901.

GEORGE HOWLETT DAVIS.
